UNITED STATES PATENT OFFICE.

JOSEPH G. O'KELLY, OF CHICAGO, ILLINOIS.

HEAT-GENERATOR.

SPECIFICATION forming part of Letters Patent No. 793,219, dated June 27, 1905.

Application filed March 23, 1903. Serial No. 149,133.

To all whom it may concern:

Be it known that I, JOSEPH G. O'KELLY, a citizen of the United States, and a resident of Chicago, in the county of Cook and State 5 of Illinois, have invented certain new and useful Improvements in Heat-Generators, of which the following is a full, clear, and exact description.

The object of my invention is to provide a 10 heat-generator, and particularly stoves for domestic uses which can use either hard or soft coal and burn both the solid as well as the gaseous elements of the same and dispose of the heat products produced by their consumption in such manner that the heat will 15 directly affect the exterior walls of the stove while *en route* to the chimney and assist in the generation of gases from the unconsumed fuel supplied to the stove. This I accomplish by the means hereinafter fully described, and as particularly pointed out in the claims.

In the drawings, Figure 1 is a vertical central section taken through a stove embodying my invention. Fig. 2 is a horizontal section taken on dotted line 2 2, Fig. 1, looking in the direction indicated by the arrows.

Referring to the drawings, A represents the base of a heating-stove which is supported on suitable legs and in turn supports the side walls *a* of the lower chamber of the stove. The ash-pit of the stove is partitioned off within these side walls *a* by the vertical wall *b*, and access is had to such ash-pit by a suitable hinged or sliding door *B*. The top of the lower chamber is covered by a transverse plate *c*, and the area of the ash-pit is such that the lower end of the centrally-located fire-pot *C* and the grates *D* enter 35 the same as shown. The space inclosed between the side walls *a* and the walls of the ash-pit form an air-chamber *d*, into which access is had through a door *e*, which has a slide-valve therein for regulating the supply 40 of air into said chamber according as desired.

Resting on and arising from the diaphragm or plate *c*, just outside of and concentric with the fire-pot, is a circular wall *E*, 45 whose upper edge terminates in the same

horizontal plane as said fire-pot. The outward inclination of this wall *E* is not quite so great as that of the fire-pot, and consequently the base of the same is farther from the fire-pot than the upper edge thereof. The dia- 55 phragm or plate *c* between the base of wall *E* and the diaphragm is cut away from a point immediately next the wall of the ash-pit on one side clear around the outside of said ash-pit to the opposite side wall thereof to form 60 an air-inlet *f* of such capacity that the air will, when the stove is in operation, fill the space between said fire-pot and wall *E* and discharge evenly up from between the upper edges thereof all the way around. 65

Located preferably equidistant from the axial center of the fire-pot and from each other a suitable distance outside of wall *E* are the standards *g g*. These are suitably secured to and arise from diaphragm *c* and 70 have resting on their upper ends the lower edge of the lower section *F* of a circular magazine. The upper edge of this lower section is rabbeted or bell-shaped and has seated therein the upper section *G* of the 75 magazine, and the upper end of this upper section is preferably reduced in diameter and extends to and through the top *h* of the stove, where it is closed by a suitably removable cover *H*. 80

Between the top of the stove and the diaphragm and supported by the latter is the outer cylinder *I*, which is greater in diameter than and surrounds and incloses the magazine in such manner as to leave an annular 85 chamber *J* around said magazine extending from the diaphragm to the top of the stove.

At a point just above the upper edges of the fire-pot and wall *E* the lower section of the magazine is provided with an annulus *K*, 90 which is secured to its inner surface. The inner circumference of this annulus corresponds to that of the circumference of the inner side of the upper edge of the fire-pot, and it has its upper and lower edges beveled, the latter 95 at a greater angle than the former, to provide a slanting roof *k* over the spaces between the upper edge of the fire-pot and wall *E* and between the latter and the lower section of the magazine, so as to provide for a 100

restricted passage at the point where the gases and products of combustion from the fire-pot and magazine will as they escape therefrom thoroughly commingle with the heated air issuing and discharging upward from between the fire-pot and wall E.

The operation of my invention is as follows: A fire being built in the fire-pot, to which access from the outside of the stove is had 10 through a door M, opening into the magazine as shown, the draft through the door e of the air-chamber d is closed and that through the door B is opened. In order to assist in getting the fire started, a damper N in the shoulders of the section of the magazine can be 15 opened; but when the fire is well started this damper is closed and the draft through door B is closed or regulated, so that but very little air passes therethrough. The draft through door e is then opened and the air from chamber d passes up between the fire-pot and wall e and passes between and out at the upper edges thereof and commingles with the gases generated by the fire in the fire-pot and together therewith passes down 20 between wall E and the lower section of the magazine and under the lower edges thereof and then up between the outer casing of the stove and the magazine. The heat adjacent 25 to the upper edges of the fire-pot and wall E is sufficient to produce combustion, and this combustion continues from this point down under the lower edge of the lower section of the magazine and upward until the gases of 30 combustion have been consumed.

A hopper O, of fire-brick or other suitable material, may, if desired, be seated against the upper beveled surface of the annulus, and when supplying fuel to the stove I prefer to pile the same up as far as the upper 40 dotted line x. (Shown in Fig. 1 of the drawings.) The heat derived from the sides of the magazine is sufficient to coke this fuel and liberate a large per cent. of the gas therefrom, and this gas escapes and burns the same as the gas from the bed of fuel in the fire-pot, which will during the operation of the stove get more or less candescent up as far as the dotted line y. (Shown in Fig. 1.) 45 The operation of my invention thoroughly consumes the particles of carbon thrown off by the burning fuel and likewise consumes the products of combustion so thoroughly as to destroy the smoke.

The principal feature of my invention is 50 the extraction of the gas from the stove at a point below the upper surface of the body of fuel in the combustion-chamber and the burning of the gas so generated by supplying 55 thereto and commingling therewith air in a more or less heated condition; and it also consists in the utilizing of the heat so produced—namely, by the combustion of these gases to heat the exterior of the stove. In 60 the accomplishment of these objects I do not

wish to be confined to the exact construction of the exterior of the stove or the shape of the magazine or the shape of other elements or parts of the invention as hereinbefore described, because these may be changed or in 70 some instances omitted without departing from the spirit of my invention.

What I claim as new is—

1. A heat-generator comprising a fire-pot, a surrounding concentric wall separated 75 from and about the same height as said fire-pot, a suitable supporting-plate therefor having openings therein between the base of said wall and said fire-pot, a magazine surrounding said wall the lower edge of which terminates a suitable distance above said supporting-plate, an annulus secured to the inner circumference of said magazine having its 80 upper and lower edges beveled interiorly and overhanging said fire-pot and surrounding wall, and an outer shell or casing closed at its top and provided with a chimney-opening.

2. A heat-generator comprising a fire-pot, a surrounding concentric wall separated from and about the same height as said fire-pot, a suitable supporting-plate therefor having openings therein between the base of said wall and said fire-pot, a magazine surrounding said wall the top of which is normally 90 closed and the lower edge of which terminates a suitable distance above said supporting-plate, an annulus secured to the inner circumference of said magazine having its upper and lower edges beveled interiorly and overhanging said fire-pot and surrounding 95 wall, and an outer shell or casing closed at its top and provided with a chimney-opening.

3. A heat-generator comprising a basal chamber divided into an ash-pit and an independent air-chamber, a fire-pot the lower 105 grated end of which extends into said ash-pit, a transverse plate or diaphragm covering said ash-pit and air-chamber, a wall surrounding said fire-pot the base of which is farther removed from said fire-pot at its base 110 than at its upper edge which is supported by said diaphragm, which latter has openings therein connecting said air-chamber with the space between said fire-pot and wall, a magazine surrounding said wall the lower edge of 115 which is suitably supported above said diaphragm, an annulus secured to the inner circumference of said magazine the upper and lower edges of which are interiorly beveled and which overhangs the outer edge of said fire-pot, and a suitable exterior shell or case for said generator.

4. A heat-generator comprising a basal chamber divided into an ash-pit and an independent air-chamber, a fire-pot the lower 125 grated end of which extends into said ash-pit, a transverse plate or diaphragm covering said ash-pit and air-chamber, a wall surrounding said fire-pot the base of which is farther removed from said fire-pot at its base 130

than at its upper edge which is supported by said diaphragm, which latter has openings therein connecting said air-chamber with the space between said fire-pot and wall, a magazine surrounding said wall the top of which is normally closed and the lower edge of which is suitably supported above said diaphragm, an annulus secured to the inner circumference of said magazine the upper and lower edges of which are interiorly beveled

and which overhangs the outer edge of said fire-pot, and a suitable exterior shell or case for said heat-generator.

In testimony whereof I have set my hand this 17th day of March, 1903.

JOSEPH G. O'KELLY.
